United States Patent Office

Des. 211,804
Patented July 30, 1968

211,804

TOY HELICOPTER

Robert Genin, Scarsdale, N.Y., assignor to Child Guidance Toys Inc., Bronx, N.Y., a corporation of New York

Filed July 18, 1967, Ser. No. 7,848

Term of patent 14 years

(Cl. D34—15)

Fig. 1.

Fig. 2.

FIG. 1 is a perspective view of my design for a toy helicopter having a transparent fuselage which exposes the internal gearworks for operating the propeller blades and the wheels;

FIG. 2 is a top plan view of the helicopter;

FIG. 3 is a front end view of the helicopter; and

FIG. 4 is a rear end view of the helicopter.

I claim:

The ornamental design for a toy helicopter, substantially as shown and described.
